(57) **CLAIM**

The ornamental design for a recoil cover for an internal combustion engine, as shown and described.

DESCRIPTION

FIG. 1 is a top perspective view of a recoil cover for an internal combustion engine according to the present invention;

FIG. 2 is a bottom perspective view of the recoil cover of FIG. 1;

FIG. 3 is a top view of the recoil cover of FIG. 1;

FIG. 4 is a bottom view of the recoil cover of FIG. 1;

FIG. 5 is a back view of the recoil cover of FIG. 1;

FIG. 6 is a front view of the recoil cover of FIG. 1;

FIG. 7 is a first side view of the recoil cover of FIG. 1; and,

FIG. 8 is a second side view of the recoil cover of FIG. 1.
